UNITED STATES PATENT OFFICE.

RUDOLPH F. STEHLIK, OF CHICAGO, ILLINOIS, ASSIGNOR, BY MESNE ASSIGNMENTS,
TO AUTOMATIC ELECTRIC INC., OF CHICAGO, ILLINOIS, A CORPORATION OF DELA-
WARE.

TELEPHONE SYSTEM.

Application filed August 22, 1924, Serial No. 733,471. Renewed May 7, 1928.

The present invention relates in general to telephone systems, but is concerned more particularly with telephone systems of the type in which so-called "finder switches", i. e., 5 backward hunting switches, are employed to connect a calling line with an idle trunk; and the principal object, briefly stated, is the production of a new and improved finder system employing primary finders which are directed in their movements by registering equipment operated from the calling line, and 10 employing also secondary finders which are not directed but perform the usual testing operation to determine the extent of their 15 hunting movement.

One of the main features of this invention is that the common line relays, of which there are twenty for each group of one hundred lines, are used as counting relays to count off the impulses transmitted to a primary finder as it is being directed to the calling line.

Another feature of this invention relates to the provision of novel circuit arrangements whereby the negative line conductors are normally connected to the common tens line relays and are switched to the units line relays as soon as the tens registration is completed.

30 A further feature of the invention relates to the provision, in connection with the twin 35 finder allotters which operate in conjunction with each other to allot one idle finder of a group as large as the combined capacity of both allotters, of means whereby these finder allotters are electrically interlocked so as to cause them to operate in synchronism with each other to prevent simultaneous allottement by both allotters.

40 A further feature relates to the centralized control of the switch-through operation which is performed only after a primary finder has found the calling line and a secondary finder has found the primary finder.

45 There are various other features of the invention, having to do, however, for the most part, with the circuit details involved in carrying out the features hereinbefore set forth, which, together with the foregoing, will be explained fully hereinafter.

50 Referring now to the accompanying drawings, comprising Figs. 1-4, inclusive, which show by means of the usual circuit diagrams a sufficient amount of apparatus in a sys-

tem embodying the principles of the invention to enable the invention to be understood and its utility appreciated, Fig. 1 shows the primary finder PF which has access to the line of substation A; Fig. 2 shows the secondary finder allotter SFA and the secondary finder SF which has access to the primary finder PF, and which is linked to the selector S; Fig. 3 shows the common line relays (which are subsequently used as impulse counting relays), together with certain auxiliary relays; and Fig. 4 shows the primary finder allotters PFA-1 and PFA-2, together with the associated allotter control and sending control relays.

Regarding the equipment shown in the drawings, it may be pointed out that the sub-station A is of the usual automatic type; that the primary finder PF, together with the selector S, is of the well known vertical and rotary type of automatic switch and has its bank contacts arranged in horizontal rows or levels; and that the secondary finder SF, together with the secondary finder allotter SFA and the primary finder allotters PFA-1 and PFA-2, are of the well known rotary type of switch in which the wipers move in a forward direction only and advance upon the backward stroke of the stepping magnet rather than upon the forward stroke. 70 75 80

In order to enable the system to be understood best, it will be assumed that the subscriber at substation A, whose line terminates in the tenth set of bank contacts in the sixth level of the primary finder PF, as is denoted by the number 60 placed to the left of substation A, desires to make a call. Accordingly, the subscriber at substation A removes his receiver, thereby placing a direct current bridge across conductors 2 and 3. The positive conductor 3 of the line of substation A is connected through the resting contact and armature 6 of the cut-off relay 4, and conductor 8 to the sixth positive common line conductor 206, which is grounded through a resting contact and an armature of relay 251. Accordingly, a circuit is closed through the calling line and over the negative line conductor 2, resting contact and armature 5, conductor 7, armature 254 and its resting contact, and conductor 216 for both windings of the sixth tens relay 236. Relay 236 thereupon energizes and locks itself at 100

armature 255 and through the locking chain circuit to the holding conductor 288 which is grounded through the resting contact and armature 316 of relay 303, Fig. 4, and armature 328 and its resting contact. Armature 255 of the tens relay 236 also opens at this point the locking chain circuit which is provided in order to prevent two or more tens relays from becoming locked up on simultaneous calls. As a further result of the energization of relay 236, it places ground on the tens operating conductor 281 at armature 258. The fact that the tens operating conductor 281 is grounded by the sixth tens relay 236 and not by some other tens relay pre-determines that the tens digit to be transmitted is the tens digit 6 as will hereinafter appear.

As a still further result of the energization of relay 236, it closes at armature 255 a circuit for relay 251 which thereupon energizes and removes ground from conductors 201-210, inclusive, leaving conductor 206, however, grounded at armature 259 of relay 236. As a further result of the energization of relay 251, it closes at its inner upper armature a circuit from the grounded holding conductor 288 for the multi-contact transfer relay 253 which thereupon energizes and locks itself to ground through the lower armature and working contact of relay 251, at the same time opening its initial circuit. Relay 253 transfers the one hundred negative conductors, of which conductor 7 is one, from the tens operating conductors 211-220, inclusive, to the units operating conductors 221-230, inclusive. Responsive to this operation, the tenth units relay 250 energizes over the following circuit: from ground by way of armature 259 of the sixth tens relay 236 and its working contact, conductor 206, conductor 8, armature 6 and its resting contact, the calling line, resting contact and armature 5, conductor 7, armature 254 and its working contact, the tenth units conductor 230, the associated armature and resting contacts of relay 252, and relay 250 to battery. Upon energizing, relay 250 places ground upon the units operating conductor 284 at its upper armature. The fact that the units operating conductor 284 is grounded by the units relay 250 and not by some other units relay pre-determines that the units digit to be transmitted subsequently is the units digit 0 as will hereinafter appear. Relay 250 also locks itself to the grounded conductor 288 at its lower armature, and at its middle armature places ground on start conductor 285, thereby closing a circuit for the cut-off relay 252. Relay 252 thereupon energizes and disconnects the units conductors 221-230, inclusive, from the corresponding units relays 241-250, inclusive. Relay 252 also closes a multiple circuit for relay 253 at its upper armature for reasons that will appear hereinafter.

As a further result of the placing of the ground potential upon start conductor 285 by relay 250, a circuit is closed through armature 315 and its resting contact of relay 303, Fig. 4, for start relay 304. Start relay 304 thereupon energizes and places ground upon wipers 348 and 358 of the primary finder alloters PFA-1 and PFA-2, respectively. Wiper 358 of the primary finder allotter PFA-2 at this time is out of engagement with its bank and accordingly nothing happens responsive to ground being placed thereon. However, wiper 348 of the primary finder allotter PFA-1 is in engagement with the first contact in its bank and the ground potential is extended over conductor 46 to relay 23 of the allotted primary finder PF. Accordingly, relay 23 energizes and prepares the finder for operation and connects up the common conductors 41 and 42, and 44 and 45.

As a still further result of the energization of start relay 304, Fig. 4, it closes at armature 319 and its right hand working contact a circuit for the upper winding of the two step relay 301 as follows: from ground by way of the third armature (counting from the top) of relay 235, Fig. 3, and its resting contact, working contact and armature 258, the tens operating conductor 281, resting contact and armature 309, armature 319 and its right hand working contact, armature 311 and its resting contact, and the upper winding of relay 301 to battery. Relay 301 now energizes, but owing to the fact that the upper winding of relay 301 comprises a comparatively small number of turns of wire having a relatively high resistance, relay 301 energizes rather weakly and operates only its first step armature 312 which closes a locking circuit for the lower winding through the working contact and armature 322. However, as long as the initial circuit of the upper winding of relay 301 is established, the lower winding of the said relay 301 is short circuited.

As a still further result of the energization of the start relay 304, it places ground on the interrupter 339 at armature 319 and its left hand working contact in order to start the sending operation. Accordingly, as soon as the interrupter 339 is closed a circuit is closed through armature 310 and its resting contact, tens operating conductor 282, the corresponding armature and its resting contact of relay 261, and the upper winding of the tens pick-up relay 261 to battery. Relay 261 also is a two step relay and, therefore, energizes only enough to operate its lower armature, which is a first step armature. Upon being operated, the lower armature of relay 261 closes a locking circuit including both windings of the relay in series. However, this locking circuit is not effective at this time, owing to the fact that the initial circuit is still established, and the ground potential applied to the junction of the two wind-

ings short circuits the lower winding of the relay. However, as soon as the interrupter 339 opens the initial circuit of the upper winding of relay 261, the locking circuit 5 through the two windings in series becomes effective and the relay energizes completely, and at its inner upper armature disconnects conductor 282 from the junction of its own windings and connects it instead through the 10 inner upper armature of relay 262 and its resting contact to the junction of the windings of relay 262.

The inner upper armature of relay 262, it will be noted, is connected through conductor 15 283 to the common vertical magnet operating conductor 42, Fig. 4, which is at this time connected with vertical magnet 26 of the primary finder PF, Fig. 1, through the working contact and armature 38 of relay 23. Accordingly, upon the next closure of the interrupter 339, the ground potential which is placed on conductor 282 is extended by way of conductor 283 to the vertical magnet operating conductor 42 and thence to vertical magnet 26 of the primary finder PF, Fig. 1. The momentary application of ground to conductor 282 is effective also in operating relay 262 through its first step to close a locking circuit for itself at its lower armature, and 25 when the ground potential is removed from conductor 282 relay 262 energizes completely and removes ground at its upper armature from the contact of the second armature, counting from the top, of relay 231. This 30 latter operation, however, does not have any particular utility at this time on account of the fact that relay 231 is not the tens relay which is energized. In addition, relay 262 closes at its upper armature a circuit for relay 263 which energizes and connects conductor 288 with the lower armatures of relays 232-240, inclusive, over a path that is exclusive of the lower armatures of relays 231-239, inclusive. Relay 262 also extends conductor 35 283 to the first tens relay 231.

Similarly, upon the next momentary application of ground potential to conductor 282 by the interrupter 339, an impulse of current is again transmitted to the vertical magnet 26 of the primary finder PF, Fig. 1, and a circuit is closed through the upper winding of relay 231 to operate the relay through its 40 first step, and at the termination of the momentary application of ground potential relay 231 energizes completely and prepares relay 232 for operation.

This operation continues as described until six impulses of current have been delivered to vertical magnet 26, at which time the tens relays 232-234, inclusive, in addition to the tens relay 231, have been operated fully and the tens relay 235 is energized through its 45 first step. At the end of the sixth impulse transmitted to vertical magnet 26, ground is again removed from conductor 282 by the in-

terrupter 339, whereupon the fifth tens relay 235 energizes completely and at its third armature, counting from the top, removes ground from the tens operating conductor 281, ground having been supplied previously, 50 as hereinbefore pointed out, through the armature in question and its resting contact, and the working contact and armature 258 of the sixth tens relay 236.

Responsive to the six impulses of current 55 delivered to it, vertical magnet 26 of the finder PF raises the wipers 71-73, inclusive, step by step and they come to rest opposite the sixth level of bank contacts.

Responsive to the removal of ground potential from the tens operating conductor 281, the interrupter 339 is rendered ineffective to further operate the vertical magnet of the primary finder PF, and the lower winding of relay 301, Fig. 4, being no longer short circuited, energizes in series with the upper winding of the relay and operates the armature proper through its second step. At armature 311 relay 301 disconnects the right hand working contact of relay 319 from the junction of its own windings and connects it instead to the junction of the windings of relay 302; disconnects the interrupter 339 from the tens operating conductor 282 at armature 310 and connects it instead to the units operating conductor 286; and at armature 309 disconnects armature 319 of relay 304 from the tens ground conductor 281 and connects it instead to the units ground conductor 284. When this occurs armature 319 is grounded again through conductor 284, and the interrupter 339 again becomes effective. Also, a circuit is closed through the right hand working contact of relay 319 and armature 311 and its working contact for the two-step relay 302, 60 which thereupon energizes through its first step as pointed out in connection with relay 301.

Upon the first closure of the interrupter 339 subsequent to the above mentioned operation of relay 301 through its second step, a circuit is closed through armature 310 and its working contact and over the units operating conductor 286 for the upper winding of the two-step units pick-up relay 264, which thereupon energizes part way only, as pointed out in connection with the corresponding tens pick-up relay 261. Accordingly, at the end of this closure of the interrupter 339, relay 264 energizes fully and disconnects the units operating conductor 286 from the junction of its own windings and connects it instead to the corresponding armature of relay 265 and to conductor 287 which is connected to the rotary magnet operating conductor 41, Fig. 4.

Upon the next closure of the interrupter 339, ground is again placed upon the units operating conductor 286 momentarily and the upper winding of relay 265 is energized, operating the relay through its first step. Also,

ground is placed through conductor 287 on the common rotary magnet operating conductor 41, thereby closing a circuit through the working contact and armature 39 of relay 23 of the primary finder PF, Fig. 1, for the rotary magnet 27. At the end of this momentary application of ground to conductor 286, relay 265 energizes completely and extends conductor 286 to the upper winding of the first units relay 241. At its upper armature, relay 265 closes a circuit for relay 266 which energizes and shunts the associated chain circuit.

In the above manner the relays 242-249, inclusive, are operated, and as relay 249 is operated through its first step the tenth impulse of current is delivered to rotary magnet 27 over the above pointed out path. At the opening of the interrupter 339 following the tenth impulse to rotary magnet 27 of the primary finder PF, Fig. 1, the two-step relay 249 energizes through its second step and at its middle upper armature removes ground from the working contact and upper armature of the tenth units relay 250 and, accordingly, from the units ground conductor 284.

In the primary finder PF, the rotary magnet 27 energizes responsive to each of the ten impulses of current delivered to it and rotates the wipers 71-73, inclusive, step by step until they come into engagement with the tenth set of bank contacts in the sixth level, which is the contacts 9-11, inclusive, associated with the line of substation A.

As a result of the ground potential being removed from the units ground conductor 284, the interrupter 339 is rendered ineffective and the two-step relay 302 operates fully through its two windings in series, owing to the fact that its lower winding is no longer short circuited. At its upper armature 313 relay 302 places ground upon conductor 332 preparatory to operating the switching relay 21 of the primary finder PF, Fig. 1. However, assuming that a secondary finder has not yet found the trunk associated with the primary finder PF, the secondary test relay 305 is not yet energized and the switch-through circuit is open at armature 323 of relay 305. Also, it may be pointed out that relay 306 is at this time energized in a manner and for a purpose to be hereinafter explained, and maintains conductor 332 disconnected at armature 326 from the stepping relay 345 of the finder allotters.

Returning now to the point at which start relay 304 first energized, this relay at armature 320 places ground through armature 325 and its resting contact on the common conductor 44, thereby extending ground through armature 41 of relay 23 of the primary finder PF, Fig. 1, to the individual secondary finder start conductor 52 of the finder. When this occurs, a circuit is closed through the jumper 68, the common secondary group start conductor 58, and the resting contact and arma-

ture 156 for start relay 148 of the secondary finder allotter SFA. Start relay 148 thereupon energizes; applies ground at armature 154 to test wiper 142 through test relay 147; and at armature 153 connects the interrupter 150 to stepping magnet 104 of the secondary finder SF through wiper 141 and the bank contact on which it is standing. Accordingly, stepping magnet 104 advances the wipers 101-103, inclusive, step by step in search of the primary finder PF under the control of the interrupter 150.

When the wipers 101-103, inclusive, arrive upon the bank contacts in which conductors 55-57, inclusive, terminate, a circuit is completed for test relay 147 as follows: from ground by way of the working contact and armature 154 of start relay 148, test relay 147, normally closed contacts controlled by armature 151, wiper 142, the bank contacts upon which it is standing, test wiper 102 of the secondary finder SF, the bank contact upon which it is standing, conductor 56, jumper 66, conductor 50, armature 36 of relay 23 and its working contact, the common test conductor 45, and relay 305 and resistance 331, Fig. 4, in multiple to battery. Responsive to the closure of this circuit test relay 147 energizes and at armature 151 disconnects the interrupter 150 from magnet 104 of the secondary finder SF, and closes a locking circuit for itself through magnet 104, at the same time disconnecting its own winding from wiper 142. Relay 147 also applies ground to wiper 143, thereby closing a circuit for the secondary finder connecting relay 105. Relay 105 thereupon energizes; connects up its line wipers 101 and 103 at armatures 109 and 108; connects the release trunk conductor 113 of the associated selector S with the test wiper 102 at armature 106; and at armature 107 connects ground to release trunk conductor 113 and to test wiper 102.

Regarding the secondary test relay 305, Fig. 4, it may be pointed out that this relay is shunted by the non-inductive resistance 331 in order to permit the test relay 147 of the secondary finder allotter SFA, Fig. 2, to energize quickly over the above traced circuit. Accordingly, relay 305 will probably not operate as quickly as relay 147 and will remain unoperated while relay 147 is energizing and becoming locked up, as hereinbefore pointed out. However, when the direct ground potential is placed upon test wiper 102 of the secondary finder SF by relay 105, as pointed out above, test relay 305, Fig. 4, energizes quickly. Upon energizing, relay 305 disconnects ground from the common start conductor 44 and closes a locking circuit for itself at armature 325. Accordingly, ground is extended through conductor 45, working contact and armature 36, conductor 50, jumper 66 and conductor 56 to test wiper 102 of the secondary finder SF, thereby providing a

holding circuit for relay 105 through armature 106 and its working contact and the working contact and armature 107 independent of the ground supplied to relay 105 from relay 147 through wiper 143.

As a result of the ground potential being placed upon release trunk conductor 113 of the selector S by the operation of relay 105, as above pointed out, a circuit is closed 10 through wiper 144 of the secondary finder allotter SFA for the start-relay-disconnect relay 149 and for stepping magnet 145 in multiple. Relay 149, upon energizing, disconnects start relay 148 at armature 156. 15 Start relay 148, however, being slow acting, does not fall back immediately. Stepping magnet 145, upon energizing, attracts its armature preparatory to advancing the wipers 141-144, inclusive, but does not advance 20 these wipers upon its forward stroke. Stepping magnet 145 opens a point in its own circuit at armature 146, but does not open its own circuit on account of the fact that the interrupter contacts 146 are at this time 25 shunted by armature 155 and its working contact.

When start relay 148 finally falls back, it opens the circuit of test relay 147 at armature 154, whereupon relay 147 deenergizes 30 and removes ground from wiper 143 at armature 152, leaving relay 105 locked up from the ground potential coming over the hereinbefore traced circuit from the secondary test relay 305, Fig. 4. Test relay 147 also removes 35 the shunt from around the interrupter contacts 146 at armature 155, whereupon stepping magnet 145 deenergizes and advances the wipers 141-144, inclusive, into engagement with the next set of bank contacts. If 40 the finder associated with this next set of bank contacts is idle the stepping magnet 145 is not again operated and relay 149 deenergizes and connects start relay 148 to the start conductor 58 again. However, if the finder 45 is busy, test wiper 144 engages a ground potential upon the test contact thereof; relay 149 remains energized; and stepping magnet 145 operates again to advance the wipers to the next contact. This operation continues 50 until an idle finder is found, whereupon test wiper 144 engages an ungrounded contact; stepping magnet 145 ceases to operate; and relay 149 deenergizes and connects start relay 148 to start conductor 58 again.

55 Referring now again to Fig. 4, as a further result of the energization of relay 305, it connects the grounded conductor 332 to the allotter test relay 346 at armature 324, whereupon relay 346 energizes and closes at armature 352 a circuit for stepping magnets 349 and 354 in multiple. These stepping magnets thereupon energize preparatory to advancing their respective wipers. As a still further result of the energization of relay 305, it connects at armature 323 ground from the

grounded conductor 332 to the wipers 347 and 357 of the first and second allotters, respectively. Wiper 357 is not in engagement with a bank contact at this time. However, wiper 347 is in engagement with the bank contact 70 in which the switching conductor 47 of the primary finder PF terminates. Accordingly, the ground potential is extended to the switching conductor 47, and switching relay 21 of the primary finder PF energizes through off normal contacts 30 and armature 37 and its working contact. Upon energizing, relay 21 locks itself to the release trunk conductor 50 of the primary finder PF, which is at this time grounded over conductor 45 80 by the secondary test relay 305, Fig. 4, as hereinbefore pointed out. Relay 21 also places ground upon test wiper 72 of the finder at armature 33, whereupon the cut-off relay 4 of the calling line energizes and disconnects 85 the conductors 7 and 8 from the calling line at armatures 5 and 6, respectively. Relay 21 also connects up the line wipers 71 and 73 at armatures 34 and 40, respectively. When this occurs, the line relay 121 of the selector 90 S energizes over the calling line through bank contacts 9 and 11, wipers 71 and 73, armatures 34 and 40 and their working contacts, conductors 49 and 51, jumpers 65 and 67, conductors 55 and 57, the bank contacts in which these 95 conductors terminate, wipers 101 and 103, armatures 109 and 108 and their working contacts, conductors 112 and 114, and armatures 126 and 129 and their resting contacts. Line relay 121, upon energizing, closes at armature 100 124 a circuit for release relay 122 which thereupon energizes and places ground upon release trunk conductor 113 at armature 125, so as to maintain the calling line in connection with the first selector after the ground potential placed on the release trunk conductor through the medium of the primary finder allotter PFA-1 has disappeared. 105

Referring now again to Fig. 4, as a further result of the operation of armature 324 of the secondary test relay 305, the winding of relay 303 is energized in multiple with the allotter test relay 346 through the working contact and armature 318 of relay 304. Upon energizing, relay 303 disconnects start conductor 285 at armature 315 from start relay 304. Start relay 304, being slow acting, does not deenergize immediately following its disconnection at armature 315. As a further result of the energization of relay 303, ground is 110 removed from the holding conductor 288 at armature 316, whereupon the tens relays 231-236, inclusive, relays 261, 262 and 263, the units relays 241-250, inclusive, and relays 264, 265 and 266 deenergize. 115

Upon the deenergization of the tens relays, the circuit of relay 251 is opened. Relay 251 deenergizes and again grounds the conductors 201-210, inclusive, at the same time opening the initial circuit of relay 253, leav- 120 125 130

ing relay 253 energized, however, over start conductor 285 and through the working contact and upper armature of relay 252.

The units relays 241-250, inclusive, upon deenergizing, remove ground from start conductor 285, leaving this conductor grounded, however, at armature 315 of relay 303, Fig. 4. Accordingly, relays 252 and 253 remain energized and no other number can as yet be registered.

When start relay 304, Fig. 4, finally falls back, it disconnects the winding of relay 303 from in multiple with test relay 346 and connects it to the grounded test wiper 347 at armature 318. Relay 304 also removes ground from conductor 290 at armature 322, whereupon relays 301 and 302 deenergize. Start relay 304 also removes ground from wiper 348 of the allotter PFA-1, whereupon the holding relay 23 of the primary finder PF deenergizes and places ground at armature 37 upon test conductor 47 through the off normal contacts 30 so as to maintain the primary finder PF busy to the primary allotter PFA-1 until the primary finder PF has become idle and has been restored to its normal position. As a further result of the deenergization of start relay 304 it opens the locking circuit of relay 305 at armature 320, whereupon relay 305 deenergizes.

As a result of the deenergization of relay 302 and of the deenergization of relay 305, the local circuit of the allotter test relay 346 is opened at armatures 313 and 324. When this occurs, the test relay 346 deenergizes, regardless of the fact that test wiper 347 is in engagement with a grounded bank contact, because the interrupter contacts 350 and 355 are open. Upon deenergizing, relay 346 opens the circuit of magnets 349 and 354, whereupon these magnets deenergize, and each advances its respective wipers one step. In this case the wipers 357 and 358 of the primary finder allotter PFA-2 are advanced still further off their bank contacts, and the wipers 347 and 348 of the primary finder PFA-1 are advanced into engagement with the second set of bank contacts. Assuming that the primary finder associated with this second set of bank contacts is idle, the test conductor thereof corresponding to test conductor 47 is ungrounded and test relay 346 is not again energized, permitting the allotters to remain where they are. Also, relay 303, which is now connected to test wiper 347, deenergizes and disconnects start conductor 285 from ground and connects it to start relay 304 again.

Relays 252 and 253, Fig. 2, now deenergize to permit the number of the next calling line to be registered.

Referring now to the connection which is being established, the subscriber at substation A may now manipulate his calling device in accordance with the first digit in the

desired number. When he does so, one or more interruptions are produced in the circuit of line relay 121 of the selector S, Fig. 2. Accordingly, line relay 121 deenergizes one or more times and causes the wipers 130-132, inclusive, to be raised opposite the desired level of bank contacts in the usual and well known manner. The selector S now rotates its wipers 130-132, inclusive, automatically in search of an idle trunk. When an idle trunk is reached, which trunk it will be assumed is the one comprising conductors 133-135, inclusive, the switching relay 123 energizes in the usual manner; opens the circuit of the slow acting release relay 122 at armature 128; opens the test circuit and prepares the holding circuit at armature 127; and at armatures 126 and 129, disconnects conductors 112 and 114 from the windings of line relay 121 and extends them by way of wipers 130 and 132, the bank contacts upon which they are standing, and conductors 133 and 135 to the windings of the line relay associated with the seized trunk.

The line and release relays (not shown) of the seized trunk now energize and the latter places ground upon release trunk conductor 134, thereby establishing the usual holding circuit.

The calling subscriber may now manipulate his calling device in accordance with the remaining digits in the desired number and thereby complete the connection.

When the subscriber at substation A replaces his receiver after the conversation is terminated, ground is removed from release trunk conductor 134 of the trunk seized by the selector S, Fig. 2, in the well known manner, whereupon switching relay 123 of the selector S, relay 105 of the secondary finder SF, switching relay 21 of the primary finder PF, and cut-off relay 4 of the calling line deenergize. Responsive to the deenergization of switching relay 123 of the selector S, the said selector is restored to normal position in the usual manner.

Responsive to the deenergization of switching relay 21 of the primary finder PF, the release magnet 24 is energized over the following circuit: from ground by way of armature 111 of the secondary group busying relay 110, Fig. 2, and its resting contact, conductor 54, jumper 64, conductor 48', spring 29 of the push button 28 and its lower contact, armature 35 and its resting contact, resting contact and armature 31, off normal spring 25 and its upper contact, and release magnet 24 to battery. Upon energizing over this circuit, release magnet 24 restores the wipers 71-73, inclusive to normal position in the usual manner. The circuit of release magnet 24 is opened by off normal spring 25 when the wipers reach their normal position.

The manner in which a typical connection is established having been described, certain

points not fully brought out in the foregoing will now be taken up.

In commercial systems of this general type, it is generally considered to be essential that provisions be made to prevent the wrong operation of a finder when two lines accessible thereto and located in different tens groups are calling simultaneously. Otherwise the numbers of the two lines might become broken up or scrambled, so to speak. The way in which this is prevented in the present system will now be explained. For this purpose it will be assumed that the subscriber at substation A, whose line is No. 60 from the stand-point of the primary finder PF, removes his receiver and that the subscriber on line No. 71 removes his receiver simultaneously. Accordingly, the sixth tens relay 236, Fig. 3, energizes over the line of substation A in the hereinbefore described manner, and the seventh tens relay 237 energizes simultaneously. Relay 236, upon energizing, closes a locking circuit for itself at armature 255, at the same time removing ground from the corresponding locking armature of relay 237. Therefore, relay 236 alone locks itself energized. Relays 236 and 237 close a circuit for relay 251, whereupon relay 251 energizes and removes ground from conductors 201-210, inclusive, leaving the sixth conductor 206 grounded however, through armature 259 and its working contact of the sixth tens relay 236. There is no ground on the seventh conductor 207, however, regardless of the fact that relay 237 is energized, owing to the fact that ground is disconnected from the upper armature of relay 237 at armature 259 of relay 236. Relay 251 also closes at its lower armature a circuit for the multi-contact transfer relay 253, whereupon conductor 7 and the similar conductors of the other lines are disconnected from the tens relays and transferred to the units relays. The tenth units relay 250 now energizes over the calling line as hereinbefore pointed out. The first units relay 241, however, does not energize, even though the subscriber on line 71 has his receiver off the hook, because of the fact that the positive conductor of the calling line 71 is now ungrounded because ground is removed from the corresponding conductor 207, it being understood that the positive conductors of all lines whose first digit is 7 are connected to conductor 207 through the contacts of their respective cut-off relays in the same manner that the positive conductor of the line of substation A is connected to conductor 206 through the contacts on the cut-off relay 4. It will be understood also that relay 237, not being locked up, falls back upon the above described energization of relay 251.

A further point somewhat related to the one explained above is that in case two lines in the same tens group are calling simulta-

neously only the lowest number is registered, owing to the fact that each units relay, barring the last, removes ground from the locking armature of the next units relay. Accordingly, as soon as the cut-off relay 252 energizes the relay which is not locked up falls back leaving the other units relay locked up. 70

It sometimes happens that a subscriber takes off his receiver and replaces it again without actually making a call. He may do this so quickly that a tens relay becomes locked up, but sufficient time is not allowed for a units relay to operate. It is, accordingly, desirable to automatically unlock the tens relay after a slight interval so that the next calling line may energize the correct tens relay. Accordingly, upon any tens relay energizing, timing conductor 289 is grounded through the upper armature and resting contact of relay 261, closing a circuit for the slow to pull up relay 308. Relay 308 energizes after a slight interval and closes a circuit for relay 307 at armature 329. Relay 307, accordingly, energizes after a momentary interval and removes ground from the holding conductor 288 at armature 328 in case start relay 304 has not become energized. Responsive to the removal of ground from conductor 288, the locked up tens relay de-energizes and removes ground from the timing conductor 289, whereupon relays 308 and 307 fall back one after the other and relay 307 replaces ground upon conductor 288. 95

It may happen occasionally that a primary finder, such for example as the primary finder PF, Fig. 1, finds the calling line but the primary finder is not in turn found by a secondary finder, such for example as the secondary finder SF, Fig. 2. In this case, if special provisions were not made the entire group would be tied up and rendered inoperative because the registering relays are locked up and are not unlocked ordinarily until the primary finder has found the calling line and has been found by a secondary finder. When such a contingency arises, however, a special timing arrangement including relays 306-308, inclusive, comes into play after sufficient time has been allowed for a secondary finder to find the primary finder and causes the allotters to be advanced and the register relays to be unlocked. The way in which this is accomplished will now be explained. It has been pointed out hereinbefore that conductor 288 is grounded upon the energization of any one of the common tens relays of Fig. 3, and that relays 307 and 308 energize as a result. As a further result of the energization of relay 307, it closes a circuit for the slow acting relay 306 at armature 327, whereupon relay 306 energizes and disconnects conductor 332 from the working contact of armature 318 at armature 326, so as to prevent a premature advance of the allotters. Now, when pick-up relay 261, Fig. 130

3, energizes, it opens the circuit of relay 308 at its upper armature. Accordingly, at the end of the total time for which they are adjusted, the three relays 306-308, inclusive, 5 are deenergized. The adjustment of these relays is such that this total time is sufficient to permit a secondary finder to find a primary finder, allowing the maximum required hunting time. Upon deenergizing, relay 306 10 closes at armature 326 a circuit for test relay 346 which has been prepared at armature 313, whereupon test relay 346 energizes and closes at armature 352 a circuit for stepping magnets 349 and 354 in multiple. These 15 magnets accordingly energize preparatory to the advance of the associated wipers. The winding of relay 303 is energized in multiple with relay 346 through the working contact and armature 318 and removes ground from the locking conductor 288 at armature 316 and at armature 315 disconnects start relay 20 304 with the result that start relay 304 deenergizes after a slight interval and opens the circuit of relay 302 at armature 322 which 25 deenergizes and opens the circuit of relays 303 and 346 at armature 313, whereupon relay 346 deenergizes and opens the circuit of stepping magnets 349 and 354 at armature 352 whereupon the said stepping magnets de- 30 energize and the allotters are advanced in the usual manner one step.

Responsive to the removal of the ground potential from conductor 288, the locked up tens and units relays deenergize and, responsive 35 to the removal of ground from conductor 285 at armature 315, relays 252 and 253, Fig. 3, deenergize, permitting the number of the calling line to be registered again with the result that the sending operation is 40 started all over again and the newly allotted primary finder finds the calling line and a secondary finder in the associated group finds the primary finder in the manner hereinbefore described.

45 The manner in which the two primary finder allotters PFA-1 and PFA-2 are kept in exact step with each other will now be pointed out. For this purpose it will be assumed that the two allotters are advanced one 50 step automatically from their position shown in the drawing in the hereinbefore described manner and that the finders associated with the next three or four contacts in the bank of the allotter PFA-1 are busy. Accordingly, test wiper 347 engages a grounded test contact and the winding of relay 303 is maintained energized through the resting contact and armature 318 and maintains the start conductor 285 grounded and start relay 60 304 disconnected at armature 315, and conductor 288 ungrounded at armature 316. Under this condition, when both stepping magnets 349 and 354 have restored to their normal position, a circuit is closed for test 65 relay 346 in multiple with the upper wind-

ing of relay 303 through contacts 350 and 355. When this occurs, and not until this occurs, stepping relay 346 energizes again and again closes the circuit of the stepping magnets at armature 352, at the same time closing a locking circuit for itself at armature 353. This locking circuit remains established until both magnets have energized far enough to permit their respective pawls to each engage the next notch on its associated ratchet wheel. When 70 this occurs, the circuit of stepping relay 346 is opened at contacts 351 and 356 and the said relay 346 deenergizes and opens the circuit of the stepping magnets 349 and 354, whereupon the said magnets deenergize and each 75 advances the respective associated wipers another step. This operation continues as described until wiper 347 engages an ungrounded bank contact at which point relay 346 fails to energize again and relay 303 deenergizes to permit the next call to be handled by the newly allotted finder.

From the foregoing it will be seen that the circuit of the magnets 349 and 354 and the controlling relay 346 are so interlocked that 80 relay 346 cannot energize to energize the stepping magnets for the next stroke until both magnets have restored their armatures and advanced the wipers to the desired set of contacts, and that, having once energized, relay 85 346 remains locked up until both magnets have operated sufficiently to insure that the wipers of both allotters will be advanced when the magnets fall back.

Referring now particularly to Figs. 1 and 100 2, the trunking arrangement between the primary and secondary finders will be explained more in detail. It will be understood, of course, that the secondary finder SF is merely one finder of the group of finders having access to the primary finder PF, Fig. 1, and others. There are a plurality of such groups of secondary finders, because one group of finders can have access to only a limited number of primary finders. If it is assumed that 105 there are fifteen groups of secondary finders and that there are thirty primary finders, such as the primary finder PF, Fig. 1, all having access to the same group of subscribers' lines, then two primary finders in this group 110 are allotted to each secondary group. This, of course, is the usual expedient made use of in order to increase the trunking efficiency by arranging it so that a call from any line 115 may be completed by a secondary finder in 120 any one of the fifteen groups.

In order to enable the primary finders to be cross-connected at will to the secondary finders in accordance with any desired arrangement when the system is first installed and later to take care of growth and traffic changes, the intermediate distributing frame IDF has been provided and each primary finder is connected to the left hand side of 125 the frame in the manner shown in the draw- 130

ings. Similarly, the bank contacts of the secondary finder are connected to the right hand side of the intermediate distributing frame in the manner shown. The same applies to the common start conductors of the various secondary groups, such, for example, as the common start conductor 58 of the secondary group in which the secondary finder SF is located. The same applies to 5 the conductors 53 and 54 associated with the make-busy relay 110.

It will be noted that there are six conductors coming from the primary finder PF to the intermediate distributing frame, 15 which are connected by means of the jumpers 63-68, inclusive, to six conductors on the opposite side of the frame. Accordingly, it is preferable that the terminals on the intermediate distributing frame are arranged in 20 groups of six terminals each. This, however, is for convenience only and any other desired arrangement may be employed. Assuming, however, that the terminals are so arranged, three terminals in each group on 25 the right hand side of the intermediate distributing frame represent the line and release trunk conductors coming from the bank contacts of a group of secondary finders; another represents the common start conductor of the associated group; while the remaining two represent contacts on the make-busy relay of the associated secondary group. From this, it will be seen that the common start conductor 58 is connected to 30 one terminal in each set of the groups of terminals allotted to the associated secondary group, and that the make-busy relay 110 is provided with an armature, such as armature 111, and associated conductors, such as 35 53 and 54, for each set of contacts in the banks of the associated secondary finders.

From the foregoing, it may be gathered 40 that the conductors associated with the primary finders are connected to one side of the intermediate distributing frame to terminals segregated in groups of six, one group for each finder, and that the bank conductors and associated conductors of the secondary finders are similarly connected to the opposite side of the frame. Accordingly, any primary finder can be readily cross-connected 45 to any group of secondary finders by means of jumpers, such as the jumpers 63-68, inclusive.

With the foregoing explanation in mind, 50 the operations accompanying an all-trunks-busy condition in a group of secondary finders, may be readily understood. Assuming now that each secondary finder and associated selector in the group in which the secondary finder SF and the selector S are located is busy, each of the chain relays, such as 135, is energized and a circuit is completed for the common make-busy relay 60 110. Upon energizing, relay 110 operates

each of its armatures. At armature 115, relay 110 removes battery from stepping magnet 145 of the secondary finder allotter SFA so as to prevent the needless searching of this allotter at this time, there being no finders 70 available for pre-selection. At armature 111 (a similar function is performed at each of the other armatures of the relay), relay 110 disconnects ground from conductor 54, thereby removing ground at one point from 75 the common conductor 43 over which the lower winding of relay 303, Fig. 4, is normally short circuited. It may be pointed out that the connection between conductors 64 and the conductor 43 includes the jumper 54, conductor 48', spring 29 of the push button 28 and its resting contact, armature 35 and its resting contact, resting contact and armature 31, and off normal spring 25 and its lower contact. This operation does not 80 have any particular effect at this time in case there are other primary finders available in the same group, but, is the same operation as is performed when the primary finder PF itself is actually busy. As a further result of the energization of the make-busy relay 110, Fig. 2, armature 111 applies ground to conductor 53, which ground is extended through the jumper 63 and conductor 85 48 to the test conductor 47 of the primary finder PF, which is connected to the first contact in the bank of test wiper 347 of the primary finder allotter PFA-1, Fig. 4. The primary finder PF is thus rendered busy, 90 even though it is not actually in use, to the said allotter PFA-1. Accordingly, if the allotter is at this time standing upon the contacts of the primary finder PF, as shown in the drawings, it is automatically advanced 95 in the hereinbefore described manner and another finder is preselected.

Assuming now that all the primary finders 100 accessible to the two allotters, shown in Fig. 4, become busy, or that part of the finders are 105 busy and the remaining idle ones are associated with busy secondary groups, ground is removed at all points from the common conductor 43, whereupon relay 371, Fig. 4, being no longer short circuited, energizes in 110 series with the associated resistance 330 and disconnects stepping relay 346 from the test wipers 347 and 357 at armature 372, so as to stop the automatic testing operation of the two allotters at this time. Of course the test wiper of the allotter which happens to be 115 on its bank at this time engages a grounded contact because all contacts in the bank of each allotter are grounded at this time. Accordingly, a circuit is closed through the resting contact and armature 318 for relay 303. Relay 303 energizes to prevent a call from starting until a trunk becomes available again, at which time ground is replaced on the common conductor 43 to short circuit the relay 120 371 which then deenergizes and connects up 125 130

the test relay 346 again at armature 372. When this occurs, the two allotters operate in the usual manner to pre-select an idle primary finder and relay 303 deenergizes when an idle finder is pre-selected.

5. What is claimed is:

1. In a telephone system, a plurality of lines, tens relays and units relays for registering the numbers of such lines, a connection 10 between one conductor of each line and the corresponding tens relay, a transfer relay, and means for energizing said transfer relay to disconnect each of said conductors from the corresponding tens relay and to connect such 15 conductor to the units relay corresponding to the units designation of the corresponding line.
2. In a telephone system, a plurality of lines, a line finder, tens relays and units relays, means responsive to a calling condition 20 on any one of said lines for energizing the tens relay corresponding to the tens designation of such line and for energizing the units relay corresponding to the units designation 25 of such line, means for transmitting two series of impulses to set said finder on the calling line, means including the tens relays of a lower order than the energized one for counting off and terminating the first series of impulses, and means including the units relays 30 of a lower order than the energized one for counting off and terminating the second series of impulses.
3. In a telephone system, subscribers' lines 35 divided into groups, a group of backward hunting finder switches for each group of lines and having access thereto, secondary finder switches divided into groups and having access to said first finder switches through 40 a system of trunk lines arranged so that the finders in each group of secondary finder switches has access to one finder in each primary group.
4. In a telephone trunking system, a plurality of groups of primary finder switches, a plurality of groups of secondary finder switches, the secondary finders in each group having access to a certain number of finders in each primary group, and a distributing 45 frame inserted between the said primary groups and the said secondary groups by means of which any primary finder may be readily rendered accessible to any group of secondary finders.
5. In a telephone trunking system, means 50 for connecting calling lines with trunk lines, said means comprising directly controlled primary finders for locating the calling lines, and automatic free hunting secondary finders for locating engaged primary finders and for connecting them with the said trunk lines.
6. In a telephone trunking system, serially 55 related primary and secondary finders for connecting calling lines with trunk lines, common impulse transmitting mechanism for di-

rectively operating a primary finder to connect with any calling line without testing any other lines, and means for causing a secondary finder to test said primary finders in rotation and connect with the one which is connected with the calling line.

7. In a telephone trunking system, a group of secondary finder switches, an allotter common to said switches, a plurality of groups of primary finder switches each containing a 75 finder accessible to said secondary finders, an allotter common to each primary group, and means in each primary allotter for controlling said secondary allotter.

8. In a telephone trunking system, a group 80 of primary finder switches, an allotter for pre-selecting idle primary finders, a group of secondary finders having access to a certain number of said primary finders, an allotter for pre-selecting idle secondary finders, and 85 means in the said primary allotter for controlling said secondary allotter.

9. In a telephone trunking system, primary and secondary finder switches for connecting calling lines with trunk lines, an allotter for 90 preselecting idle primary finders, and means for making an idle primary finder switch busy to said allotter in case all the secondary switches having access to such primary finder become busy.

10. In a telephone trunking system, a plurality of groups of primary finders, a group of secondary finders having access to a limited number of finders in each of said primary groups, and means effective in case all 100 said secondary finders become busy for preventing the starting of any primary finder to which such secondary finders have access.

11. In a telephone trunking system primary and secondary finder switches for connecting calling lines with trunk lines, a switching relay in each finder switch for closing the talking circuit, means responsive to a call for starting a primary finder and a secondary finder, means for energizing the 110 switching relay in the operated secondary finder when such finder finds the primary finder which has been started, and means common to a group of primary finders for holding the energized switching relay energized until 115 the started primary finder locates the calling line.

12. In a telephone trunking system primary and secondary finder switches for connecting calling lines with trunk lines, a switching relay in each finder switch for closing the talking circuit, means responsive to a call for starting a primary finder and a secondary finder, means effective only when both finder switches have stopped for energizing 120 the switching relay in the primary finder, means for energizing the switching relay in the secondary finder at once when such finder stops regardless of whether the primary finder has stopped or not, and means common to 125

the primary finder and other finders in the same group for maintaining the switching relay of the secondary finder energized in case such secondary finder stops before the primary finder.

5 13. In a finder system, subscribers' lines, tens relays normally connected to said lines, units relays, means responsive to a call for energizing the proper tens relay, and means 10 responsive to the operation of the energized tens relays for disconnecting said lines from said tens relays and for connecting them with said units relays.

14. In a finder system, tens and units relays connected to the same pole of the exchange battery, subscribers' lines, normally closed contacts through which said lines are connected to said tens relays, and normally open contacts operable to connect said lines to said 29 units relays.

15. In a finder system, tens and units relays connected to the same pole of the exchange battery, subscribers' lines, normally closed contacts through which said lines are connected to said tens relays, normally open contacts operable to connect said lines to said units relays, and means responsive to the 25 operation of any tens relay for opening the normally closed contacts and for closing the 30 normally open contacts.

16. In a finder system, tens and units relays connected to the same pole of the exchange battery, subscribers' lines, normally closed contacts through which said lines are connected to said tens relays, normally open contacts operable to connect said lines to said units relays, means responsive to the operation of any tens relay for opening the normally closed contacts and for closing the normally 35 open contacts, other contacts for disconnecting the lines from said units relays, and means responsive to the operation of any units relay for operating said other contacts.

17. In a finder system, subscribers' lines, 45 each having one conductor normally connected to the same pole of the exchange battery, tens relays normally connected between the other conductors of said lines and the other pole of the exchange battery, means responsive to the energization of any tens relays for disconnecting all said first mentioned conductors from a battery, and contacts on the energized tens relay for re-connecting to the battery the conductors of those lines which 50 have the same tens designation as the energized tens relay.

18. In a finder system, subscribers' lines, tens relays normally connected to said lines, units relays, means responsive to the operation of any tens relay for shifting the lines from the tens relays to the said units relays, and means for preventing said units relays from responding to calls over lines other than those lines which have the same tens designation as the operated tens relay.

19. In a finder system, subscribers' lines, finder switches, tens and units relays, and means for operating said relays as counting relays to control said finders.

20. In a finder system, subscribers' lines, 70 finder switches, sending apparatus for operating said finders, counting relays for controlling said sending apparatus, and means for energizing one of said counting relays over a calling subscriber's line to pre-determine the extent of a sending operation. 75

21. In a finder system, a group of subscribers' lines, a finder, relays each common to a subgroup of said lines, means for energizing one of said relays responsive to a 80 call, sending apparatus for transmitting impulses to said finder and also to said relays, the said relays responding successively, and means for stopping the transmission of impulses responsive to the energization of the 85 particular relay immediately preceding the one which energized responsive to the call.

22. In a finder system, subscribers' lines, finder switches, sending apparatus for operating said finders, counting relays, energizing circuits for said relays including said 90 lines, and other local energizing circuits for said relays controlled by said sending apparatus.

23. In a telephone system, an automatic switch, a series of counting relays, a circuit for transmitting impulses to said switch and to said relays, means for closing said circuit at one point by energizing one of said relays, and means for opening said circuit responsive to the energization of the next preceding relay by an impulse transmitted over 95 said circuit.

24. In a switch control system, an impulse transmitting circuit, a series of counting 105 relays, contacts on each relay except the first for closing said circuit, and contacts on each relay except the last for opening said circuit.

25. In a switch control system, a series of counting relays, a pair of normally open contacts on each relay except the first, a pair of normally closed contacts on each relay except the last, circuit arrangements whereby each pair of normally closed contacts is connected in series with the pair of normally open contacts on the next succeeding relay, and an impulse transmitting circuit connected in multiple to one contact of each pair of 110 normally open contacts.

26. In a switch control system, an impulse transmitting circuit, a series of counting relays, a plurality of branches of said circuit, the number of branches being one less than the number of relays, contacts on each relay except the first for closing one of said branches, and contacts on each relay except the last for opening the branch which is adapted to be closed by the next succeeding 125 relay. 130

27. In a telephone system, lines, a switch having access to said lines, relays common to said lines, each of said relays having one terminal connected to the same terminal of battery, means for closing a circuit through certain of said relays and a calling one of said lines in series to operate them to register the number of said lines, and means for operating said switch under the control of said relays to establish a connection with said line.
28. In a finder system, a group of subscribers' lines divided into a plurality of sub groups, two motion finder switches having access to said lines, a register relay for each of said sub groups, means responsive to the initiation of a call on one of said lines for energizing the register relay corresponding to the sub group containing the calling line, a second group of register relays corresponding in number to the number of lines in each of said sub groups, means responsive to the energization of said sub group register relays for connecting said second group of register relays to the line in the sub group containing the calling line, means controlled over the calling line for energizing the register relay corresponding thereto, and means controlled by said energized register relay and the deenergized register relays of lower

order for directing one of said finders to establish a connection with said calling line.

29. In a finder system, a group of subscribers' lines divided into a plurality of sub groups, two motion finder switches having access to said lines, a register relay for each of said sub groups, means responsive to the initiation of a call on one of said lines for energizing the register relay corresponding to the sub group containing the calling line, a second group of register relays corresponding in number to the number of lines in each of said sub groups, means responsive to the energization of said sub group register relay for connecting said second group of register relays to the line in the sub group containing the calling line, means controlled over the calling line for energizing the register relay corresponding thereto, means responsive to the energization of said line register relays for disconnecting the remainder of said line register relays from said lines, and means controlled by said energized relay and the deenergized register relays of the lower order for directing one of said finders to establish a connection with said calling line.

In witness whereof, I hereunto subscribe my name this 19th day of August, A. D., 1924.

RUDOLPH F. STEHLIK.
